UNITED STATES PATENT OFFICE.

JOB HUTCHINSON, OF BROOKLYN, NEW YORK.

CHANGEABLE INDICATOR.

1,345,675.

Specification of Letters Patent.

Patented July 6, 1920.

Application filed December 4, 1917. Serial No. 205,351.

To all whom it may concern:

Be it known that I, Job Hutchinson, a citizen of the United States, residing at Brooklyn, in the county of Kings and State of New York, have invented new and useful Improvements in Changeable Indicators, of which the following is a specification.

This invention relates to changeable indicators in general and pertains particularly to changeable indicators for railway stations. The invention provides novel indicating apparatus for exhibiting the data for the track number, list of stations, and time of departure.

15 The invention provides an apparatus having means within convenient reach of the operator for changing and adjusting all display data, and also means for bringing within reach for adjustment the display apparatus which ordinarily is in position at the top of the structure well above the head of the operator or passenger.

Among other features of invention in the apparatus is the particular mechanism for 25 the combined lifting of the station list curtain and lifting of the display rack bearing the time data.

Another feature of the invention is the mechanism for winding the station curtain 30 list roll and maintaining a constant tension on the curtain in whatever position it may be, whether in the extended exhibiting position or in the lowered position wound on its roller.

35 Another feature of the invention provides for the use of springless curtain rolls and provides mechanism adapted to receive the curtain roller and provided with tension means adapted to engage said roller to exercise the tensioning action.

The invention provides balanced mechanism for moving the display apparatus thus relieving the operator of much of the trouble and care incident to present day apparatus.

45 The above objects and advantages of the invention will be described and claimed in the following specification and claims and illustrated in the accompanying drawings, 50 in which—

Figure 1 represents a front elevation of the apparatus showing the relative positions of the track number data, the time card

rack, and the station list curtain when the latter is partly raised;

55 Fig. 2 is a sectional view taken through the center of Fig. 1 and illustrating the position of the relative parts for displaying data and the lighting arrangements for illuminating the same;

60 Fig. 3 represents an enlarged view of the mechanism used for elevating the time card rack and raising the station list curtain;

Fig. 4 is a side view of the structure shown in Fig. 3, showing in dotted lines the 65 pivotal action of the display rack;

Fig. 5 is an enlarged view of the roller and gearing structure shown at the bottom of Figs. 3 and 4 constituting apparatus for the reception of the ends of a curtain roller;

70 Fig. 6 is a view taken on the line 6—6 of Fig. 5 looking in the direction of the arrow;

Fig. 7 is a view, partially in section, of the curtain roller showing the adjustable end connection and the spring for holding 75 the same in place;

Fig. 7^a is an end view of the roller with the end connection removed and illustrating the series of openings adapted to receive the pin carried by the end connection;

80 Fig. 7^b is a perspective view of the end connection used with the roller illustrated in Fig. 7;

Fig. 8 is a view similar to the view shown in Fig. 3, but representing a modification 85 of the mechanism in which there is a single drive chain having two chains positioned to carry the time card rack;

Fig. 9 is a side view of the mechanism shown in Fig. 8;

90 Fig. 10 represents a modification of the structure in which the track number cage is secured to the endless chain and adapted to move up and down with the time card rack. The dotted lines indicate the position 95 of the cage when lowered;

Fig. 11 illustrates a front view of the structure shown in Fig. 10 but with the time card rack in its raised position and the track number cage in the display position;

100 Fig. 12 represents a sectional view taken on the line 12—12 of Fig. 10;

Fig. 13 represents a modification of the arrangement illustrated in Fig. 10, showing the time card rack formed in combination 105 with the track number data and adapted to

be raised or lowered, the lighting for this data being illustrated as provided by an attachment secured to the outside of the upper extension of the apparatus; and

5 Fig. 14 represents a fragmentary view enlarged of the sectional portion illustrated in Fig. 12.

Fig. 15 is a sectional view taken on line 15—15 of Fig. 1;

10 Fig. 16 is an enlarged view of a portion of the curtain end showing the eyelet for the reception of the hook on the chain;

15 Fig. 17 is an enlarged side view illustrating the relative position of the hook with the curtain in position thereon and showing how the end of the hook is covered by the time card rack.

Like numerals refer to like parts throughout the drawings.

20 Referring in detail to the structure shown in Figs. 1 and 2, 1 represents the main supporting uprights at the side of the apparatus. 2 indicates an ornamental finishing strip on the front face of the structure and it will be observed that the lower portion of 25 the strip 2^a is separated from the upper portion and is mounted on hinges 3 to swing from the closed position against the face of the apparatus to the open position as indicated in Fig. 2. 4 represents pivotally mounted doors or panels extending the full front width of the machine and adapted to provide supporting racks 5 for the storage of rollers 6 bearing the station list data.

30 The doors 4 are so mounted that the weight of the rolls or the weight of the racks is sufficient to hold the door in the closed position by means of the weight of the rolls being swung past the pivot point. Likewise, the 40 door is adapted to remain in the open position by reason of the fact that it is pivoted at a point nearer the base of the door than the upper side thereof. Above the topmost door 4 is a narrow door 7 pivoted along its 45 lower edge by the hinges 8 and adapted to open for the insertion of one of the rollers 6 into the apparatus as will be hereinafter described.

The entire assembly of the indicator is 50 adapted to display the necessary track number data at the top of the structure in addition to the traveling card time display rack which is adapted to move in conjunction with the curtain carrying the station list data. In the constructions indicated the track number data is shown as located in an angular extension projecting forwardly at the top of the apparatus so that the data may be seen from either side of the structure. The projecting housing for the track 60 number data is indicated by the numeral 9. Within the projection 9 is located the necessary means for illumination as indicated by the lamp 10 located behind the track number data and also the lamp 11 having the reflec-

70 tor adapted to project the light downwardly upon the time card rack and station list curtain. This reflector is preferably rigidly attached to the projection 9 and is indicated by the numeral 12.

75 The operating apparatus provided for the movement of the display parts of the structure will be understood from the following description. At the top of the structure is a cross frame member 13 and immediately below the frame member 13 is a rotatable horizontal shaft member 14 adjustably connected at either end to the frame member 13 by the screw-threaded rods 15 having suitable fastening nuts 16. The ends of the 80 shaft member 14 are provided with collars 17 adapted to hold the shaft 14 in proper position in the bearings 18 provided at the lower end of the screw-threaded rods 15. In the lower part of the apparatus, about opposite the door 7, and within convenient reach of the operator there is a horizontal roller 19 mounted in supporting bearings 20 located at the sides of the apparatus. The roller 19 is provided with the sprocket wheels 22 90 rigidly connected thereto and adapted to drive an endless chain member 23 which extends around the sprocket wheels 22, upwardly, and over corresponding sprocket wheels 24 which are rigidly secured to the 95 cross shaft 14. In the form illustrated in Figs. 1, 2, 3, and 4 two endless chains are provided and these chains are adapted to carry fastened thereto a display time card rack and the curtain carrying the station list 100 data, and also the balance-weight as will be hereinafter described.

105 Referring in detail to the time card display rack as illustrated in Figs. 1-4, it will be seen that a cross yoke member 25 is secured to the chain members 23 to be moved up and down according to the movement of the chain and that the cross yoke member 25 is positioned laterally by means of its end 110 extensions 26 being adapted to slide on the guideway 27 extending vertically at either side of the structure. The time card rack 28 is pivotally attached at its upper edge to the cross yoke member 25 by the hinge members 29. Immediately behind the time 115 card rack 28 is a hook member 30 secured to each of the chains 23 and adapted to receive the end of the station list curtain 6^a and to lift the same into the display position. The present apparatus provides for 120 the placing of the hooks 30 behind the time card rack 28 and positioned near the top of the latter. Movement of the time card rack by swinging the lower end forwardly and upwardly uncovers the hooks so as to allow the attachment of the end of the display curtain on the same and when the display rack is swung back into its normal position it comes into contact with the ends of the hooks 30 to effectively prevent the dislodg- 125 130

ment of the end of the display curtain from the hooks. This is an important feature necessary in the movement of the curtain into the display position and also during the lowering of the curtain to be wound on the curtain roll. The chains 23 hang from the upper sprocket wheels 24 and substantially vertically from either side of said sprockets. A balance-weight 31 is securely fastened to the chains 23 on the side of the sprocket wheels 24 opposite to the display rack 28. The weight 31 is designed to substantially balance the weight of the display rack and the weight of the display curtain so as to reduce the effort necessary in the operation of the machine.

Referring in detail to the structure adjacent the roller 19, it will be observed that this roller is provided with cylindrical portions 19^a having a diameter as great as the sprocket wheels 22, this being for the purpose of protecting the surface and material of the display curtain from contact with the end of the sprocket teeth during the movement of the curtain. At either side of the entire structure are supporting bearing members 32 having the bearings 20 in their upper portion to receive the ends of the roller 19. At each end of the roller 19, 30 is a beveled gear 19^b adapted to mesh with corresponding beveled gears 19^c mounted in the upper portion of the members 32. Stub shafts 33 are connected to the gears 19^c and are adapted to be turned by any suitable handle, not shown, so as to operate the roller 19 and gears 22 to elevate the rack 28 and the hooks 30. Immediately below the roller 19 and mounted in the members 32 are the gears 34 of the spur type which are rigidly fastened to a shaft 35 carrying the disks 36 adapted to receive the ends of the curtain rollers. The disks 36 are provided with the cross slots 37 which provide the openings for the reception of the ends of the rollers as will be described. Immediately behind the gears 34 are corresponding spur gears 38 which are in mesh with the gears 34 and which are rigidly mounted on a cross shaft 39 journaled at either end in the block members 32. Rigidly keyed to the shaft 39 are the two drums 40 to which are attached steel tape 41 which is adapted to be wound on the drum. This tape 41 extends upwardly to the top of the entire apparatus and passes over a pulley 42 which is carried by the cross frame member 13 and from the pulley 42 the free end of the tape hangs downwardly and is provided with a tension weight 43.

Referring in detail to the roller indicated by 6 in Figs. 2 and 10 and which is illustrated in detail in Fig. 7, and which is adapted to carry the curtain bearing the station list data, 44 represents the main cylindrical part of the roller having a central

bore at either end indicated by the numeral 45. A plate member 46 is adapted to fit over the end of the bore 45 and have its extension 47 project into the bore for a short distance. A set screw 48 extends through the end wall of the part 44 and securely fastens the plate member 46 over the end of the roller. A series of small openings 49 are provided around the surface of the plate member 46 and are adapted to receive a pin 50 projecting from the end block 51 which is adapted to be inserted into the openings 37. This block member 51 is provided with a shank 52 which is adapted to extend through a central opening 46^a in the plate member 46 and project into the bore 45 where a spring 53 is adapted to be fastened to the end of the same and to be compressed when the shank member 52 is drawn through the plate member 46. The necessity of adjusting the block 51 on the end of the roller is caused by the fact that the length of the curtains vary and that the pick-up rod on the end of the curtain must hang in the proper position to be lifted and placed on the hooks 30. By drawing out the block 51 and removing the pin 50 from the opening 49, the curtain may be wound up or unwound with respect to the block 51 in order to take up the slack in the curtain.

In the operation of the apparatus a roller 6 is inserted through the space uncovered by the door 7 and the end blocks 51 of the roller are slipped into the receiving openings 37 and at the same time the rod, not shown, in the end of the curtain is hooked over the hooks 30 which are uncovered when the time card rack 28 is lifted. When the stub shaft 33 is turned, the gears 19^c and 19^b operate to lift the curtain and the display rack. At the same time the turning movement of the roller 6 turns the disks 36 and through the gears 34 and 38 wind up the steel tape 41 on the drums 40, thus elevating the weight 43. In apparatus heretofore in use it has been customary to use curtain rollers having springs adapted to provide the tension on the curtain such as would be necessary to keep the curtain taut and to provide the necessary force to wind up the curtain on the roller when the curtain is lowered. Spring rollers have proved unsatisfactory because of the fact that a constant tension was not provided. The present invention provides for this constant tension by the use of the apparatus herein described which is not limited by springs or other apparatus which ordinarily is in need of constant attention. The stub shafts 33 are provided with any convenient pawl and ratchet combination 33^a such as may be necessary to hold the stub shaft in any particular position.

Referring in detail to the structure shown

in Figs. 8 and 9 it will be observed that a single drive chain 23 is used and that the display rack and its balance-weight are fastened at the opposite ends of additional chains 23^a which are hung over sprocket members located on the cross shaft 14. In this case there is but a single hook 30 which is provided on the chain 23 in the middle of the structure.

10 Referring to Figs. 10 and 11, it will be observed that these views illustrate a modification in which the cage carrying the track number is fastened to the endless chain 23 and is adapted to be moved up or down as is necessary in the changing of the track number data.

15 In Fig. 12 is shown a sectional view of the construction taken on line 12—12 of Fig. 10. Fig. 14 is an enlarged fragmentary 20 view of Fig. 12. These views illustrate the position of the guide strip member 27 as constituting the slidable mounting for the time card rack and the track number cage.

25 In Fig. 13 the track number cage is illustrated as providing also space for the time card rack and in this instance the display rack is not needed below the cage as is the case in the form illustrated in Figs. 16 and 11. In the form shown in Fig. 13 the 30 lighting for the station curtain is shown as provided by a lamp attached to the immediate front of the projection 9. It will be noted that the arrangement of lighting is different in the form shown in Fig. 13 35 from that shown in Fig. 10 in which latter the cage is adapted to be moved up or down without interfering with the lighting means which latter is adapted to project into the rear of the cage from the supporting member carrying the lamp bracket.

40 One of the important features of the invention is to be found in the construction of the indicator and in the particular manner in which the construction provides for 45 the covering of the interior of the structure to hide the space behind the chains 23. The invention provides for vertical panel sections 54, shown as three in number, extending from the top of the structure to the bottom of the track curtain display space.

50 The panels 54 are mounted in the same vertical plane with the chains 23 and fill the space between the chains and between the chains and the side walls of the structure.

55 The hooks 30 and the cross yoke member 25 with the time card rack are mounted on the chains 23 and positioned to move immediately in front of the panel sections 54. Fig. 1 illustrates the panels 54 and the position of the chains between the panels. Figs. 12 and 14 show the panels constructed of three ply veneer and fastened to a cross brace member 55 by means of screws 56. These sectional views illustrate also the

chains 23 positioned between the panel sections 54. 65 57 indicates an angle corner plate member to brace the member 55.

Fig. 15 represents a sectional view taken on line 15—15 of Fig. 1 and shows the panels 54 in position and fastened to a 70 cross brace member 55. The rear wall of the structure is indicated at 58 and the front 75 finishing strip at 2. The panels are illustrated as of wood but this construction may be substituted by sheet metal or wall bored construction as may be desired. The panels provide a finished appearance as well as closing the inside of the structure from dirt and from damage which may be caused by curious or mischievous parties.

80 From the present description considered in view of the apparatus disclosed it will be clear that an unusually simple apparatus is provided for bringing the display parts of a changeable indicator into easy and accessible positions for the control by the operator. Further it will be clear that the present invention provides for the tensioning of the display curtain and dispenses with all complicated mechanism involving 85 the use of springs or clockwork. Also it will be observed that the moving parts are substantially balanced and that but little power need be exercised in order to operate the stub shafts to move the apparatus.

90 Change in size and shape of the parts as well as in the material of construction may be made without departing from the scope of the invention.

95 What I claim is:—

100 1. In a changeable indicator, a frame, an upper rotatable member mounted on said frame, a lower rotatable member mounted on said frame and below said upper rotatable member, an endless flexible connection passing over said upper and said lower rotatable members and extending between the same, a traveling display device mounted on said flexible connection, a balance weight mounted on said flexible connection on the opposite side of said rotatable members from said display device, and means to transmit power to one of said rotatable members to move said flexible connection.

105 2. In a changeable indicator, a frame, an upper rotatable member mounted on said frame, a lower rotatable member mounted on said frame and below said upper rotatable member, an endless, flexible connection passing over said upper and said lower 110 rotatable members and extending between the same, a traveling display device mounted on said flexible connection, a balance weight mounted on said flexible connection on the opposite side of said rotatable members from said display device, means to transmit power to one of said rotatable members to move said flexible connection, curtain end sup-

porting means carried by said flexible connection, and a display curtain adapted to engage said curtain end supporting means.

3. In a changeable indicator, a frame, an upper rotatable member mounted on said frame, a lower rotatable member mounted on said frame and below said upper rotatable member, an endless flexible connection passing over said upper and said lower rotatable members and extending between the same, a traveling display device mounted on said flexible connection, a balance weight mounted on said flexible connection on the opposite side of said rotatable members from said display device, means to transmit power to one of said rotatable members to move said flexible connection, curtain end supporting means adapted to be moved by said flexible connection and located to the rear of said traveling display device, and a display curtain adapted to engage said curtain end supporting means.

4. In a changeable indicator, a frame, an upper rotatable member mounted on said frame, a lower rotatable member mounted on said frame and below said upper rotatable member, an endless flexible connection passing over said upper and said lower rotatable members and extending between the same, a traveling display device mounted on said flexible connection, a balance weight mounted on said flexible connection on the opposite side of said rotatable members from said display device, means to transmit power to one of said rotatable members to move said flexible connection, curtain end supporting means adapted to be moved by said flexible connection and located to the rear of said traveling display device, and a display curtain adapted to engage said curtain end supporting means.

5. In a changeable indicator, a frame, an upper rotatable member mounted on said frame, a lower rotatable member mounted on said frame and below said upper rotatable member, an endless flexible connection passing over said upper and said lower rotatable members and extending between the same, a traveling display device mounted on said flexible connection, a balance weight mounted on said flexible connection on the opposite side of said rotatable members from said display device, means to transmit power to one of said rotatable members to move said flexible connection, curtain end supporting means carried by said flexible connection, a curtain roller mounted below said lower rotatable member, and a display curtain rolled upon said curtain roller and having the outer end projecting from the lower side of said curtain roller and upwardly parallel to said flexible connection and extending over the front surface thereof to engage said curtain end supporting means.

6. In a changeable indicator, a frame, an upper rotatable member mounted on said frame, a lower rotatable member mounted on said frame and below said upper rotatable member, an endless flexible connection passing over said upper and said lower rotatable members and extending between the same, a traveling display device mounted on said flexible connection, a balance weight mounted on said flexible connection on the opposite side of said rotatable members from said display device, means to transmit power to one of said rotatable members to move said flexible connection, curtain end supporting means carried by said flexible connection, a curtain roller mounted parallel with the axis of said rotatable members, a display curtain mounted on said roller and adapted to engage said curtain end supporting means, a tension weight, a reel member connected to said roller and adapted to be turned thereby, and a flexible weight connection extending from said weight member and adapted to be wound on said reel member, the unwinding of said curtain from said roller serving to wind said weight connection on said reel and elevate said weight member.

7. In a changeable indicator, a frame, an upper rotatable member mounted on said frame, a lower rotatable member mounted on said frame and below said upper rotatable member, an endless flexible connection passing over said upper and lower rotatable members and extending between the same, a balance weight mounted on said flexible connection, curtain end supporting means carried by said flexible connection on the opposite side of said rotatable members from said weight, means to apply power to one of said rotatable members, a curtain roller mounted parallel with the axis of said rotatable members, a display curtain mounted on said roller and adapted to engage said curtain end supporting means, a tension weight, a reel member connected to said roller and adapted to be turned thereby, and a flexible weight connection extending from said weight member and adapted to be wound on said reel member, the unwinding of said curtain from said roller serving to wind said weight connection on said reel and elevate said weight member.

8. In a changeable indicator, a frame, an upper rotatable member mounted on said frame, a lower rotatable member mounted on said frame and below said upper rotatable member, an endless flexible connection passing over said upper and lower rotatable members and extending between the same, curtain end supporting means carried by said flexible connection, means to apply power to one of said rotatable members, a curtain roller mounted parallel with the axis of said rotatable members, a display curtain mounted on said roller and adapted to engage said curtain end supporting means, a primary gear rigidly mounted with respect to said roller, a secondary gear rigidly mounted with respect to said reel member and in mesh with said primary gear, a tension weight, and a flexible weight connection fastened to said weight and to said reel and adapted to be wound on said reel.

9. In a changeable indicator, a frame, an upper rotatable member mounted on said frame, a lower rotatable member mounted on said frame and below said upper rotatable member, an endless flexible connection passing over said upper and lower rotatable members and extending between the same, curtain end supporting means carried by said flexible connection, means to apply power to one of said rotatable members, a curtain roller mounted parallel with the axis of said rotatable members, a display curtain mounted on said roller and adapted to engage said curtain end supporting means.

means, a reel member, a primary gear rigidly mounted with respect to said roller, a secondary gear rigidly mounted with respect to said reel and in mesh with said primary gear, a tension weight, and a flexible weight connection fastened to said weight and to said reel and adapted to be wound on said reel.

9. In a changeable indicator, a frame, an upper rotatable member mounted on said frame, a lower rotatable member mounted on said frame and below said upper rotatable member, an endless flexible connection passing over said upper and lower rotatable members and extending between the same, curtain end supporting means carried by said flexible connection, means to apply power to one of said rotatable members, a curtain roller mounted parallel with the axis of said rotatable members, a display curtain mounted on said roller and adapted to engage said curtain and supporting means, a reel member mounted parallel with and behind said roller, a primary gear rigidly mounted with respect to said roller, a secondary roller rigidly mounted with respect to said reel and in mesh with said primary gear, a pulley wheel located adjacent said upper rotatable member, a tension weight located in the rear of said frame, and a flexible weight connection fastened to said weight and to said reel and adapted to be wound on said reel.

10. In a changeable indicator, a frame, an upper rotatable member mounted on said frame, a lower rotatable member mounted on said frame and below said upper rotatable member, an endless flexible connection passing over said upper and lower rotatable members and extending between the same, curtain end supporting means carried by said flexible connection, means to apply power to one of said rotatable members, curtain roller end supporting means rotatably mounted with the axis thereof parallel to the axis of upper and lower rotatable members, a reel member, a primary gear rigidly mounted with respect to said roller end supporting means, a secondary gear rigidly mounted with respect to said reel and in mesh with said primary gear, a tension weight, and a flexible weight connection fastened to said tension weight and to said reel and adapted to be wound on said reel.

11. In a changeable indicator, a frame, a rotatable member mounted on said frame, a flexible connection passing over said rotatable member and hanging from either side thereof, a traveling display device mounted on said flexible connection, a balance weight mounted on said flexible connection on the opposite side of said rotatable member from said display device and adapted to balance the weight of said display device, and means

to transmit power to said rotatable member to move said flexible connection.

12. In a changeable indicator, a frame, a rotatable member mounted on said frame, a flexible connection passing over said rotatable member and hanging from either side thereof, a traveling display device mounted on said flexible connection, a balance weight mounted on said flexible connection on the opposite side of said rotatable member from said display device, means to transmit power to said rotatable member to move said flexible connection, a curtain roller mounted parallel with the axis of said rotatable member, a display curtain mounted on said roller, a tension weight, a reel member connected to said roller and adapted to be turned thereby, and a flexible weight connection extending from said weight member and adapted to be wound on said reel member, unwinding of said curtain from said roller serving to wind said weight connection on said reel and elevate said weight member.

13. In a changeable indicator, a frame, a rotatable member mounted on said frame, a flexible connection passing over said rotatable member and hanging from either side thereof, a traveling display device mounted on said flexible connection, a balance weight mounted on said flexible connection on the opposite side of said rotatable member from said display device, means to transmit power to said rotatable member to move said flexible connection, a curtain roller mounted parallel with the axis of said rotatable member, a display curtain mounted on said roller, a reel member, a primary gear rigidly mounted with respect to said roller, a secondary gear rigidly mounted with respect to said reel member and in mesh with said primary gear, a tension weight, and a flexible weight connection fastened to said weight and to said reel and adapted to be wound on said reel.

14. In a changeable indicator, a frame, a rotatable member mounted on said frame, a flexible connection passing over said rotatable member and hanging from either side thereof, a traveling display device mounted on said flexible connection, a balance weight mounted on said flexible connection on the opposite side of said rotatable member from said display device, means to transmit power to said rotatable member to move said flexible connection, a curtain roller mounted parallel with the axis of said rotatable member, a display curtain mounted on said roller, a reel member mounted parallel with and behind said roller, a primary gear rigidly mounted with respect to said roller, a secondary roller rigidly mounted with respect to said reel and in mesh with said primary gear, a pulley wheel located adjacent said

5 rotatable member, a tension weight located in the rear of said frame, and a flexible weight connection fastened to said weight and to said reel and adapted to be wound on said reel.

10 15. In a changeable indicator, a frame, a rotatable member mounted on said frame, a flexible connection passing over said rotatable member and hanging from either side thereof, a traveling display device mounted on said flexible connection, a balance weight mounted on said flexible connection on the opposite side of said rotatable member from said display device, means 15 to transmit power to said rotatable member to move said flexible connection, curtain roller end supporting means rotatably mounted with the axis thereof parallel to the axis of said rotatable member, a reel member, a primary gear rigidly mounted with respect to said roller end supporting means, a secondary gear rigidly mounted with respect to said reel and in mesh with said primary gear, a tension weight, and a 20 flexible weight connection fastened to said tension weight and to said reel and adapted to be wound on said reel.

25 30 35 40 45 16. In a changeable indicator, a frame, an upper rotatable member mounted on said frame, a lower rotatable member mounted on said frame and below said upper rotatable member, an endless flexible connection passing over said upper and said lower rotatable members and extending between the same, guide means fastened to said frame, support members carried by said flexible connection, a balance weight mounted on said flexible connection on the opposite side of said rotatable members from said support members, a traveling cross frame adapted to be positioned laterally by said guide means and carried by said flexible connection, a display device pivotally mounted on said cross frame, means to transmit power to one of said rotatable members to move said flexible connection, and a display curtain adapted to engage said support members.

50 55 60 65 17. In a changeable indicator, a frame, an upper rotatable member mounted on said frame, a lower rotatable member mounted on said frame and below said upper rotatable member, an endless flexible connection passing over said upper and said lower rotatable members and extending between the same, guide means fastened to said frame, support members carried by said flexible connection, a balance weight mounted on said flexible connection on the opposite side of said rotatable members from said support members, a traveling cross frame adapted to be positioned laterally by said guide means and carried by said flexible connection, a display device pivotally mounted on said frame, means to transmit power to one of said ro-

tatable members to move said flexible connection, and a display curtain adapted to engage said support members, said support members being adapted to engage the rear face of said traveling display device to prevent the movement of said curtain from said support members.

70 75 80 85 90 95 100 105 110 115 120 125 130 18. In a changeable indicator, a frame, an upper rotatable member mounted on said frame, a lower rotatable member mounted on said frame and below said upper rotatable member, an endless flexible connection passing over said upper and said lower rotatable members and extending between the same, support means carried by said flexible connection, a balance weight mounted on said flexible connection on the opposite side of said rotatable members from said support means, a cross frame carried by said flexible connection, a traveling display device carried by said cross frame, means to transmit power to one of said rotatable members to move said flexible connection, a curtain roller mounted parallel with the axis of said rotatable members, a display curtain mounted on said roller and adapted to engage said supporting means, a tension weight, a reel member connected to said roller and adapted to be turned thereby, and a flexible weight connection extending from said weight member and adapted to be wound on said reel member, unwinding of said curtain from said roller by the movement of said endless connection serving to wind said weight connection on said reel and elevate said weight member.

130 19. In a changeable indicator, a frame, an upper rotatable member mounted on said frame, a lower rotatable member mounted on said frame and below said upper rotatable member, an endless flexible connection passing over said upper and lower rotatable members and extending between the same, a balance weight mounted on said flexible connection, curtain end supporting means carried by said flexible connection on the opposite side of said rotatable members from said weight, means to apply power to one of said rotatable members, a curtain roller mounted parallel with the axis of said rotatable members, a display curtain mounted on said roller and adapted to engage said curtain end supporting means, a traveling cross frame adapted to be positioned laterally within said frame and carried by said flexible connection, a display device pivotally mounted on said cross frame, a reel member, a primary gear rigidly mounted with respect to said roller, a secondary gear rigidly mounted with respect to said reel member and in mesh with said primary gear, a tension weight, and a flexible weight connection fastened to said tension weight and to said reel and adapted to be wound on said reel.

20. In a changeable indicator, a frame, an upper rotatable member mounted on said frame, a lower rotatable member mounted on said frame and below said upper rotatable member, an endless flexible connection passing over said upper and lower rotatable members and extending between the same, curtain end supporting means carried by said flexible connection, means to apply power to one of said rotatable members, 10 guide means fastened to said frame, a traveling cross frame adapted to be positioned laterally by said guide means and carried by said flexible connection, a display device pivotally mounted on said cross frame, curtain roller end supporting means rotatably mounted with the axis thereof parallel to the axis of upper and lower rotatable members, a reel member, a primary gear rigidly mounted with respect to said roller end supporting means, a secondary gear rigidly mounted with respect to said reel and in mesh with said primary gear, a tension weight, and a flexible weight connection fastened to said tension weight and to said reel and adapted to be wound on said reel.

21. In a changeable indicator, a frame, an upper rotatable member mounted on said frame, a lower rotatable member mounted on said frame and below said upper rotatable member, an endless flexible connection passing over said upper and lower rotatable members and extending between the same, 30 curtain end supporting means carried by said flexible connection means to apply power to one of said rotatable members, guide means fastened to said frame, a traveling cross frame adapted to be positioned laterally by said guide means and carried by said flexible connection, a display device pivotally mounted on said cross frame, a curtain roller mounted parallel with the axis of said rotatable members, a display 35 curtain mounted on said roller and adapted to engage said curtain end supporting means, a reel member mounted parallel with and behind said roller, a primary gear rigidly mounted with respect to said roller, 40 a secondary roller rigidly mounted with respect to said reel and in mesh with said primary gear, a pulley wheel located adjacent said upper rotatable member, a tension weight located in the rear of said frame, and 45 a flexible weight connection fastened to said weight and to said reel and adapted to be wound on said reel.

22. In a changeable indicator, a frame, an upper rotatable member mounted on said frame, a lower rotatable member mounted on said frame and below said upper rotatable member, an endless flexible connection passing over said upper and lower rotatable members and extending between the same, 50 curtain end supporting means carried by

said flexible connection, means to apply power to one of said rotatable members, guide means fastened to said frame, a traveling cross frame adapted to be positioned laterally by said guide means and carried by said flexible connection, a display device pivotally mounted on said cross frame, curtain roller end supporting means rotatably mounted with the axis thereof parallel to the axis of upper and lower rotatable members, a reel member, a primary gear rigidly mounted with respect to said roller end supporting means, a secondary gear rigidly mounted with respect to said reel and in mesh with said primary gear, a tension weight, and a flexible weight connection fastened to said tension weight and to said reel and adapted to be wound on said reel.

23. In a changeable indicator, a frame, an upper rotatable member mounted on said frame, a lower rotatable member mounted on said frame and below said upper rotatable member, an endless flexible connection passing over said upper and said lower rotatable members and extending between the same, a second flexible connection passing over said upper rotatable member and hanging from either side thereof, a traveling display device mounted on said second flexible connection, a balance weight mounted on said second flexible connection on the opposite side of said upper rotatable member from said display device, and means to transmit power to one of said rotatable members to move said second flexible connection.

24. In a changeable indicator, a frame, an upper rotatable member mounted on said frame, a lower rotatable member mounted on said frame and below said upper rotatable member, an endless flexible connection passing over said upper and said lower rotatable members and extending between the same, a second flexible connection passing over said upper rotatable member and hanging from either side thereof, guide means rigidly mounted with respect to said frame, a cross frame adapted to be positioned laterally by said guide means and carried by said second flexible connection, a traveling display device mounted on said second flexible connection and pivotally attached to said cross frame, a balance weight mounted on said second flexible connection on the opposite side of said upper rotatable member from said cross frame, and means to transmit power to one of said rotatable members to move said second flexible connection.

25. In a changeable indicator, a frame, a traveling support member positioned to move in a fixed path, and fixed panel members extending across substantially all of the space within said frame and being on each side of said support member, at least

a portion of said fixed path being in the same plane with one of said panel members.

26. In a changeable indicator, a frame, an upper rotatable member mounted on said frame, a lower rotatable member mounted on said frame and below said upper rotatable member, an endless flexible connection passing over said upper and said lower rotatable members and extending in a vertical path between the same, a fixed panel member on each side of said flexible connection, at least a portion of the vertical path of said endless connection being in the same plane with said panel members, a traveling display device mounted on said flexible connection and positioned in front of said panel member, a balance weight mounted on said flexible connection on the opposite side of said rotatable members from said display device, and means to transmit power to one of said rotatable members to move said flexible connection.

27. A changeable indicator comprising a

supporting frame, bearing members adjacent the top of said frame, bearing members adjacent the lower end of said frame, sprockets mounted in conjunction with said bearing members, hook carrying chains on said sprockets, a fixed panel member mounted between said chains and substantially filling the space between the chains and between the chains and said frame member, the path of travel of that portion of said chains carrying the hooks being in the plane of said panel members, a display curtain adapted for engagement with said hooks of said carrying chains, a display device carried on said chains, and power means to move said chains, said display device and said curtain being adapted to move in a vertical plane over the face of said panel member.

In testimony whereof I have hereunto set my hand.

JOB HUTCHINSON.
